MARKING MACHINE

Frank W. Reinhold and Charles E. Edwards, Beverly, Mass., assignors to United Shoe Machinery Corporation, Borough of Flemington, N. J., a corporation of New Jersey

Application June 3, 1938, Serial No. 211,505

9 Claims. (Cl. 101—110)

This invention relates to improvements in marking heads and more particularly to marking heads which are adapted to make plural lines of marking wherein one of the lines of marking is made by characters on marking wheels or like type carrying members mounted on the head, and the other line or lines are made by auxiliary type members positioned adjacent to the marking wheels.

10 An object of this invention is to provide an improved type unit for use in a marking head and also to provide an improved mounting for said type unit. To this end, and as illustrated herein, a feature of this invention consists in 15 the provision, in a marking head having type wheels rotatably mounted thereon, of type units of approximately the width of the type wheels, each type unit comprising a plurality of interfitting members with marking characters there- 20 on so arranged that the marking characters will be in alignment with and in line spaced relation to one another and to a marking wheel character which is in marking position. Also provided in the marking head is a pivoted bar for sup- 25 porting the auxiliary type units, the bar being so arranged that when it is in one of its positions of adjustment it holds the type units in intimate co-operative relation with the marking wheels and when the bar is moved to another 30 position, it will move the type units away from the marking wheels thereby allowing the marking wheels to be reset and the type units to be removed and changed at the will of the operator.

The expression "line spaced relation" as used 35 herein indicates the space between successive lines of marking.

The above and other objects of the invention will appear more fully from the following detailed description when read in connection with 40 the accompanying drawing and will be pointed out in the appended claims.

In the drawing:

Fig. 1 discloses a perspective view of a marking head with the improvements embodied 45 therein;

Fig. 2 is a sectional view of the marking head shown in Fig. 1 showing the interfitting relation of the members which constitute the type unit and the manner in which they are associated with the type wheel;

Fig. 3 is a fragmentary view of the marking head showing the mechanism for shifting the support bar and also the detent mechanism for positioning the shifting mechanism;

Fig. 4 is an exploded perspective view of the

members which comprise the marking unit, and

Fig. 5 is a bottom plan view showing the relative positions of the row of type formed by the marking head and those formed by the auxiliary members which comprise the type unit. 5

The marking head disclosed in this application may be applied to different types of marking machines, such, for example, as that disclosed in United States Letters Patent No. 960,029, granted May 31, 1910, upon an application of 10 Frank W. Merritt. The illustrated marking head is secured to the operating mechanism of the desired machine by means of cap screws passing through apertures 10 and 12 in the top plate 14 which forms a part of the marking head 15 frame. The plate 14 is provided with a pair of downwardly extending side pieces 16 and 18 in which is mounted a type wheel support 20. Rotatably mounted on the type wheel support are a number of type wheels 22, which are provided 20 with raised characters 24 and are separated by washers 23, four type wheels being shown by way of example. Mounted above the support is a type wheel shifting mechanism 26 which is arranged to move the type wheels in either 25 direction for resetting purposes. The type wheel support is provided with a heating element 28 for heating the marking characters on the marking head and spring urged detent balls 30 for holding the type wheels in their adjusted positions. 30 The construction so far described is fully shown in the United States Letters Patent No. 1,963,900, granted August 7, 1934, on application of W. E. Naugler to which reference may be had for a 35 more detailed description of the same. 35

Extending outwardly from the lower ends of the downwardly extending side pieces 16, 18, are arms 32 and 34 in which is pivotally mounted a type supporting bar 36. The type supporting bar is provided with square portions separated 40 by a series of flanges 38 disposed in alignment with the spacing washers 23 on the support 20 for the purpose of alining the type units which provide the marking head with additional lines 45 of marking with the type wheels. The type units will be described in detail further on in the specification. The bar 36 is rotated by a crank 37 fast to one end thereof (Fig. 1), the arrangement being such that when the crank is in the position shown in Fig. 1, where it is in engagement 50 with a lug 40 formed on an extension 35 of the arm 32, the type units carried by the bar 36 are held in engagement with the type wheels in the manner shown in Fig. 2. Upon movement of the crank 37 a short distance in a counter- 55

clockwise direction as viewed in Fig. 1, the type units will be moved out of the path of raised type characters 24 on the type wheels 22 thereby allowing the type wheels to be reset by the setting mechanism 26. Upon further movement in a counterclockwise direction the crank will be brought into engagement with a second lug 42 on the extension 35, in which position the type units will be moved far enough away from the type wheels so that they may be readily removed from the bar 36 and changed to suit a new marking requirement. The crank is retained in the position shown in Fig. 1 by a pin 44 which engages one side of the crank head and holds the head between it and the lug 40. The pin 44 is carried by an offset portion of the extension 35 (Fig. 3) which overlies the crank 37, the pin 44 being urged downwardly into engagement with the crank head (Figs. 1 and 3) by a spring 46 contained within the offset portion of the extension. The crank is held in its intermediate position, where the type units are just clear of the type characters 24, by a detent pin 48 carried by the crank head 39, the detent pin 48 being seated in a correspondingly located notch 50 (Fig. 3) in the extension 35, the pin 48 being urged into this notch by a spring 52 contained within the crank head 39. The crank is held in engagement with the lug 42 by the unbalanced arrangement of the crank 37 and the type units carried thereby which force the crank against the lug 42.

In marking operations, it is frequently desirable to provide two, three or more lines of marking. In the illustrated mechanism the lines of marking, additional to that provided by the wheels 22, are provided by rows of type units 54 which are of substantially the same width as the marking wheels 22 and are mounted on the bar 36 between adjacent flanges 38. As best shown in Figs. 2 and 4, the units 54 consists of pairs of elongated complementally shaped members 56 and 58. These members are notched so as to fit over the squared portions of the bar 36 and are further provided with interfitting connections adjacent to their notched portions so as to prevent an increase in the width of the unit 54 at its connection with the bar 36 (Fig. 5). The member 58 is provided with a slot 60 while the member 56 has formed thereon a narrow rib 62 arranged to fit snugly within the slot 60. A further result of this connection is that relative lateral movement of the members 54 and 56 is prevented and the members are held in alinement with one another. The ends of the members 56 and 58 adjacent to the type wheels 24 are nested in overlapping relation and their under surfaces are provided with marking characters 64 and 66 respectively (Figs. 2 and 5). The end 60 of the member 58 opposite its marking character 66 is provided with a shoulder 68 shaped to fit into a notch between successive raised characters 24 on the marking wheel 22 so that when the members 56 and 58 are in the position shown in Fig. 2, their type characters will be supported by the marking wheel 22 and the shoulder 68 will also act as a locking means to hold the wheel 22 against rotation. The marking character on the member 56 is supported against marking pressure by shoulders 70 and 72 (Fig. 4) on the member 58, which are disposed above, and in supporting relation to the character 64. In the illustrated embodiment of this invention, a fin 74 of a material having a high heat conductivity, such as copper, and of approximately the same

width as the spacing washers 23, is connected to the member 56. When the unit 54 is moved into the position shown in Fig. 2 the fin 74 will fit between adjacent type wheels thus providing a ready path for the transmission of heat from the heating unit 28 and the heated type wheels 22 to the auxiliary type members 56 and 58. The fin 74 also acts to support the member 56 against sidewise movement with respect to the type wheels and as the members 56 and 58 are 10 keyed together by their connections 60 and 62, the fin 74 will also hold the member 56 against sidewise movement. As the members 56 and 58 will receive considerable heat, their ends, which are to be handled by the operator, are preferably 15 provided with handles 76, 78 of a heat resisting material, such as "Bakelite" or the like.

While the auxiliary type units disclosed herein consist of two members, the number could obviously be increased by changing the proportions 20 of the interfitting connections in the midsections of these members which fit over the bar 36.

When it is desired to set up the illustrated marking head for a marking operation the crank 37 is moved into engagement with the lug 42, 25 thus moving the marking units carried by the bar 36 out of engagement with the type wheels 22. The type wheels are then reset by the setting mechanism 26 to provide the desired line of marking and the additional lines of marking are 30 made up by a suitable combination of the type units 54, pairs of which are assembled and then positioned on the bar 36, after which the bar is rotated to bring the type units into the position shown in Fig. 2 where they are in intimate 35 contact with the type wheels 22. When so located the characters on the type units are in line spaced relation to each other and to the character on the type wheel which is in marking position, and the type characters are also in 40 alinement with each other as shown in Fig. 5. If only one additional line of marking is needed, then the members 56 may be eliminated and the additional line provided by the members 58.

Having thus described my invention, what I 45 claim as new and desire to secure by Letters Patent of the United States is:

1. A marking head comprising a frame, type wheels rotatably mounted on said frame, said wheels having marking characters thereon thereby providing a line of marking characters, and auxiliary type units supported in cooperative relation with the type wheels, each of said units being of substantially the same width as one of the type wheels and comprising a plurality of 50 nested members having marking characters thereon disposed in line spaced relation to one another and to the row of characters on the marking wheels whereby additional lines of marking are provided.

2. A marking head comprising a frame, a pair of spaced supports on said frame, a type wheel rotatably mounted on one of said supports, a type unit mounted on the other support with one end arranged in supporting relation with the type wheel whereby it is supported against marking pressure, said type unit comprising a plurality of superimposed interfitting members individually connected with the type unit support, each of said members having a marking character on its end adjacent to the type wheel, the marking characters on said members being disposed in the plane of the wheel character in marking position and in radial alinement with the wheel thereby 75

providing a plurality of aligned marking characters in spaced relation to one another.

3. A marking head comprising a frame, type wheels provided with raised type characters rotatably mounted on said frame, a type supporting bar journaled in said frame for positioning additional type pieces in associated relation with the type characters on the type wheels, said bar having type receiving portions of non-circular cross section, a type piece mounted on said bar, the type piece having a recess therein shaped complementally to the type receiving portion of the pivoted bar for locking engagement therewith and also having a projecting portion constructed and arranged to fit between adjacent raised characters on a type wheel thereby to lock a selected character on the type wheel in marking position and also to support the type piece against marking pressure, and means for rotating the journaled bar to move the type piece out of engagement with the type wheel to permit the type wheel to be reset and the type piece to be changed.

4. A type unit for use in a marking head provided with a type disk, said type unit being of approximately the width of the type disk and comprising a pair of elongated nested members, each of said members being provided with a marking character at an adjacent end, the ends of said members having the marking characters thereon being arranged in overlapping relation with the marking characters in alignment with one another and in line spaced relation.

5. A type unit for use in a marking head provided with a plurality of heated marking wheels, said unit comprising a pair of elongated interfitting members, each of said members having a marking character thereon, and a projecting fin of high heat conductivity extending from one of said members and arranged for engagement with a marking wheel thereby to support the members against sidewise movement and to assist in maintaining the marking characters on the members at the same temperature as the characters on the marking wheels by providing a path for the ready transfer of heat from the wheels to the members.

6. A type unit for use in a marking head provided with a plurality of heated marking wheels, said unit being of substantially the same width as one of the marking wheels and comprising a pair of elongated interfitting members having mark-

ing characters thereon disposed in line spaced relation to one another, one of said members having a recess therein and the other member having a complementally shaped extension seated in said recess thereby preventing relative lateral movement of said members, and a flange of high heat conductivity extending from one of said members for engagement with adjacent marking wheels thereby to support the members against sidewise movement and to assist in maintaining the marking characters on the members at the same temperature as the characters on the marking wheels by providing a path for the ready transfer of heat from the wheels to the members.

7. A type member for use in a marking head comprising a plurality of heated type wheels and means for supporting type members in cooperative relation with the heated type wheels, said type member having a fin of high heat conductivity arranged for engagement with one of the heated type wheels to hold the type member against sidewise movement and to assist in maintaining the marking character on the type member at the same temperature as the marking characters on the type wheel by providing a path for the ready transfer of heat from the heated wheel to the type member.

8. A marking head comprising a frame, a support for one line of type on said frame, and a bar pivoted on said frame for rotation about its axis, the bar being arranged to support a second line of type in associated relation with the line of type on the support, said bar having a plurality of type receiving portions of non-circular cross section and flanges separating the type receiving portions of said bar.

9. A type unit for use in a marking head having a type piece mounted thereon, said type unit being of approximately the width of the type piece on the marking head and comprising a pair of elongated nested members each of which is provided with a marking character at an adjacent end, and complementally shaped abutting surfaces on the members adjacent to the marking characters, said marking characters being located in alignment with each other and in line spaced relation.
